UNITED STATES PATENT OFFICE.

JAMES S. THOMPSON, OF PELHAM, NEW YORK, ASSIGNOR TO THE AMERICAN BRAKE SHOE & FOUNDRY COMPANY, OF WILMINGTON, DELAWARE, A CORPORATION OF DELAWARE.

BRAKE SHOE.

1,402,115.

Specification of Letters Patent. Patented Jan. 3, 1922.

Application filed January 19, 1920. Serial No. 352,423.

To all whom it may concern:

Be it known that I, JAMES S. THOMPSON, a citizen of the United States, residing at Pelham, in the county of Westchester and 5 State of New York, have invented certain new and useful Improvements in Brake Shoes, of which the following is a specification.

This invention relates to improvements 10 in brake shoes and it consists of certain improvements in that type of shoe wherein reticulated metal strips are arranged on edge to the wearing face of the shoe and are combined with insert sections or blocks cast 15 thereon or assembled therewith as set forth in my pending applications including applications Serial Nos. 345,532 and 345,534. The object of this invention is to distribute 20 the metal of each reticulated strip in a curved or sinuous line lengthwise of the shoe so that it will not only appear discontinuously in the wearing face of the shoe but will also be located irregularly over a broader area 25 of the shoe and thereby avoid the possibility of cutting or scoring the wheel.

This invention may be embodied in car shoes or in locomotive shoes, solid or sectional and of any kind or variety, with or without reinforcing backs and with or without 30 inserts which may be cast on the strips or assembled therewith in any suitable manner. In view of the simple character of the invention and of the obvious manner in which it may be adapted to brake shoes 35 in general, I have deemed it necessary to show in the accompanying drawings only one simple embodiment thereof, and referring thereto—

Fig. 1 is a side elevation of a car shoe, 40 partly in section, illustrating the invention.

Fig. 2 is a plan view of the wearing face of the shoe.

Figs. 3 and 4 are transverse sectional views 45 on the lines 3—3 and 4—4 respectively of Fig. 1.

Referring to the drawings, the body 5 is preferably provided with a suitable reinforcing and strengthening ductile metal back 6 which may be made in any way well known 50 in the art or suitable for the purpose. A plurality of reticulated metal strips 7 are arranged on edge to the wearing face of the shoe and spaced apart between the sides of the shoe. These strips are curved or 55 waved in a more or less sinuous form length-

wise thereof, and preferably in a corresponding manner so that they may be more easily handled and disposed with reasonable regularity in the body of the shoe. Insert sections or blocks 8 of any desired metal and 60 of any suitable shapes may be cast on the strips (as shown) or assembled therewith at spaced intervals lengthwise of the shoe. The sinuous strips and the sections or blocks 65 constitute a single insert which is placed in the mold with or without the reinforcing back and the body metal is cast thereon in a solid form as shown in the drawings and in my application Serial No. 345,532 or in a sectional form as shown in my application 70 Serial No. 345,534. It will be readily understood that my present invention which consists essentially of a plurality of reticulated metal sinuous strips arranged on edge to the wearing face of the shoe, may be embodied 75 in all forms of shoes and with or without inserts so far as I am aware.

I prefer to make the strips of commercial expanded metal, but they may be made of wire mesh or other binding, bonding or 80 reinforcing reticulated metal, and the sections or blocks may be made in any shape and of any metal desired.

Owing to the peculiar structural formation of reticulated metal, and particularly 85 expanded metal, the wearing face of a shoe having such metal strips embedded therein on edge will always be of a composite character with the strip metal constantly changing 90 in position thereon. If the strips are straight 95 in form, there will be a discontinuous straight line of each strip metal constantly exposed on the wearing face. To prevent any tendency which may exist for this strip metal to cut or score the wheel this invention 100 contemplates shaping the strips in a more or less sinuous form to avoid thus exposing the strip metal in a straight line on the wearing face. It will be readily observed that the exposed parts of a sinuous strip will appear 105 in a discontinuous sinuous line on the wearing face and spread transversely over such an area that any tendency of the metal to cut or score the wheel is entirely eliminated.

The metal strips may be arranged in up-right position but I have found that the strip metal will be distributed over the wearing face of the shoe to a greater degree if the strips are arranged in an inclined position to the wearing face as shown in 110

Figs. 3 and 4, and I may use them either way with the openings of the several strips in registration or in staggered relation. And the strips may be spot-welded or otherwise secured to the back 6 if desired. I have shown the strips spaced apart at regular intervals, which is a desirable construction, but they may be arranged close together in a bundle form if preferred.

10 As before stated, I have not considered it necessary to illustrate the invention other than in a simple adaptation, for I believe that those skilled in the art will readily understand the application of the invention to the art in general and I therefore reserve the right to make all such adaptations and embodiments of the invention as may be fairly covered by the following claims:

I claim:

20 1. A brake shoe comprising a body, and a plurality of correspondingly waved strips of reticulated metal embedded in the body on edge to the wearing face of the shoe.

2. A brake shoe comprising a body, and a plurality of sinuous strips of expanded metal embedded in the body in an inclined position on edge to the wearing face of the shoe.

3. A brake shoe insert comprising a plurality of sinuous strips of reticulated metal arranged on edge to the wearing face of the insert and a plurality of sections or blocks cast on said strips and extending transversely of the wearing face of the insert and spaced apart between its ends.

35 4. A brake shoe insert comprising a plurality of sinuous strips of expanded metal arranged in an inclined position on edge to the wearing face of the insert and a plurality of sections or blocks cast on said strips and extending transversely of the insert and spaced apart lengthwise thereof.

35 JAMES S. THOMPSON.
